VENETIAN BLIND

Harry G. Balthasar, West Tower Park, Ohio, assignor to Edward J. Hoff, Cincinnati, Ohio

Application December 16, 1935, Serial No. 54,572

4 Claims.

(Cl. 156--17)

This invention relates to window shades of the type known as Venetian blinds and particularly to the slats therefor.

It is a known fact that Venetian blinds up to the present time have been too expensive for use in the average home. Also, the conventional Venetian blind has been too involved for convenient handling such as would enable the housewife to clean the same periodically without great difficulty. Moreover, the average blind employs a great many slats which are relatively heavy, that is to say, have considerable thickness. Accordingly they make up, when assembled, a bundle having considerable aggregate thickness. Thus, it may be said that the blinds have been extremely inconvenient to pack, handle, stock or ship.

Therefore, it has been the object of the present invention to provide a Venetian blind slat which is extremely light, has very little thickness, is inexpensively produced, permits the packing of the usual number of slats used in a blind into a very small bundle, and is extremely conveniently removed from the blind assembly. In view of the inexpensiveness and the convenience of removal and insertion, it is accordingly possible for the housewife to frequently change the slats. That is to say, she can remove all of the slats without much trouble and replace the same with new ones without a great deal of expense and in a very short time.

It is a further object to provide a slat for Venetian blinds which may be highly ornamental in view of its fabrication, the arrangement of elements constituting the same permitting color variations and other embellishments.

It is a still further object to provide a slat for Venetian blinds which can be formed and assembled in a continuous strip and cut to length without the necessity for subsequent operations at the ends of the slats.

One phase of the present invention may be said to reside in the discovery that a Venetian blind slat can be fabricated of a relatively light thin material having sufficient rigidity to maintain itself in flat condition, without additional support, as to its width, but not of sufficient rigidity to maintain itself in flat condition when unsupported as to the length of the slat, and to this end incorporating means for stiffening the longitudinal edges so that the slat thus formed is properly longitudinally stiffened.

Other objects and further advantages will be more fully apparent from a description of the accompanying drawings, in which:

Figure 1 is a general view of a window, showing the Venetian blind of this invention in relation thereto.

Figure 2 is a fragmentary view, showing the upper part of a window with the Venetian blind in completely elevated position.

Figure 3 is a sectional view taken on line 3-3, Figure 1, looking toward the slat closing mechanism.

Figure 4 is a fragmentary perspective view of the improved Venetian blind slat of this invention showing the elevating ribbon or cord relative thereto.

Figure 5 is a fragmentary perspective view of the slat of Figure 4, further illustrating the grommet plate thereof.

Figure 6 is a fragmentary perspective view illustrating a slat of this invention with the metal bound edges slightly modified from those of Figure 4 and illustrating a stiffening clip thereon.

Figure 7 is a fragmentary perspective view of the slat of Figure 6, the stiffening clip, which binds the portions of the slat together at the entry to the elevating ribbon or cord clearance opening, in retracted position.

Figure 8 is a fragmentary perspective view of a still further modification of the improved slat.

Figure 9 is a fragmentary perspective view of the slat showing still further modifications.

Figure 10 is a fragmentary perspective view of the improved slat showing further modifications in the structure of the edge binding strips.

Figure 11 is a fragmentary perspective view of the improved slat showing further modifications in the structure of the edge binding strips.

Referring to the drawings, illustrating an embodiment of the present invention, the conventional window frame is indicated at 30. End brackets 31 are provided for supporting the Venetian blind. These brackets are attached to the under side of the upper element 32 of the window frame. The means for supporting the Venetian blind slats 34 consists of a flat bar 33 pivotally mounted in the respective brackets 31-31, by means of trunnions 35. From this bar are suspended pairs of cloth straps 36, there being one element of each pair at each side of the slat. A lower cross bar 37 is supported on the lower ends of these straps. In each case the straps are attached to the bars by tacks. Between the elements of each bar of straps are cross strap elements 38 providing the normally horizontal supports for the slats themselves. The slats are spaced apart a distance slightly less than

their width so that when they are tilted or moved to closed position they slightly overlap.

The tilting or slat closing apparatus or mechanism is incorporated in conjunction with the upper pivotally mounted bar 33. This mechanism includes a slat adjusting cord 46 and a pull cord 59. The adjusting cord 46 effects the tilting of the slats 34 in the appropriate direction and the pull cord 59 acts to raise or lower the blind as desired. The operating mechanism to which these cords connect forms no part of the present invention and therefore is illustrated only in general so as to disclose the blind and slats in their proper operating environment.

15 As shown in Figure 4 to 11 inclusive, a variety of slat constructions may be utilized. In the preferred forms (see Figures 4, 5, 6, and 7) a grommet plate is provided. This plate may include 20 clips for closing the entrance to the clearance openings in the Venetian blind slats and preventing displacement or disalignment of the slat at either side of this open slot.

The slats are fabricated of a material which is sufficiently rigid or has enough body for maintaining a flattened condition as to width but not as to length. Among the materials possible for this use are fabrics, either heavy or filled, paper, either coated or heavy enough to come under the class described, cellulose products, etc. In other words, any material can be used coming under the general definition above given.

As heretofore stated the present slat can be formed and assembled in a continuous length or strip and cut to the exact length required for a given installation, without the necessity for subsequent operations at the ends or sides of the slats. In other words, the slat is not mounted on a frame as a part of the supporting structure of the blind, but is removably suspended on the ladder tapes. In the formation of the slats, a continuous strip of fabric may be fed from a machine incorporating the longitudinal edge reenforcing means. This continuously assembled strip is cut off to form slats of whatever length desired.

Now in view of the fact that the material used in the blind is flexible and will collapse or flex longitudinally if unsupported, reenforcing strips or edging strips are used to strengthen the slat.

50 Figures 6 and 7 illustrate in detail one form of edging strip 82. In this case the strip is of metal and is bent so as to form a hook or turned under portion 83, hooking a turned margin of the strip 84. In other words, this edging provides a double 55 bend which securely hooks the same in relation to the edge of the strip. A clip 85, used in this instance, is of U-shape with a hook margin 86 for holding it in position as it is moved from position overlapping the slot to position clear thereof.

Several other forms of edging strip are illustrated, as for example, in Figures 9 and 11. In Figure 11 the edging strip indicated at 87 is of 60 U-shape provided with a longitudinal crimp 88 which locks the strip on the edge of the material against displacement. In Figure 9 an angular edge strip 89 is employed. Specifically described this strip provides a hook portion of the same character as that employed in the form shown in Figures 5 and 6, with the exception that an additional flange 90 is provided projected angularly therefrom. Also, the edge of the material is given

a double bend, that is, angularly as at 91 and reversed upon itself as at 92 making an extremely secure hook.

It will be noted that in certain of the forms an entry slot is not shown. It will be understood that the entry slot can be used on any forms, some only having been selected for the purpose of illustrating the entry slot.

In Figures 4 and 5, grommet plates 93 are provided. These plates can be applied to any form 10 disclosed. They provide a frame for the clearance opening in the material and for the entry slot thereto in those instances where a slot is provided and are fastened in position by rolled 15 side edge portions 94.

The slot of Figures 4, 5, and 10 has wire edge inserts 96 therein. For this purpose the material is hemmed as at 97 providing piped edges. The hems may be short as in Figure 4, or extended entirely to a central line of the material 20 for reenforcing the same if desired as in Figure 10.

Figure 8 discloses a centrally disposed wood strip 98 as the reenforcing means. This strip is slightly off center so that it does not interfere with the elevating ribbon and its clearance opening in the slat. The material is overlapped to form a double thickness and is formed around the wood strip 98. In this form it is possible to eliminate the reenforcing means about the 30 entry slot.

Having described my invention, I claim:

1. A slat for a Venetian blind, comprising, a strip of flexible material having sufficient rigidity to maintain itself in flat condition crosswise but not lengthwise, stiffening strips disposed along the longitudinal edges of the slat, said slat including clearance openings permitting passage of the elevator cords of a Venetian blind therethrough and entry slots to said openings from the side edges of the slat, and plate elements marginally surrounding said openings and entry slots and extending across the width of the slat and attached to the stiffening strips thereof.

2. A slat for a Venetian blind, comprising, a strip of material having sufficient body to maintain itself in flat condition crosswise but not lengthwise, a centrally longitudinally disposed stiffening strip for said slat, said slat having clearance openings adjacent said stiffening strip and entry slots to said clearance openings from the side edges of the slat.

3. A slat for a Venetian blind, comprising, a strip of flexible material having sufficient rigidity to maintain itself in substantially flat condition crosswise but not lengthwise, stiffening strips disposed along the longitudinal edges of the slat, said slat including clearance openings permitting passage of the elevator cords of a Venetian blind therethrough and plate elements marginally surrounding said openings, and extending across the width of the slat and attached to the stiffening strips thereof.

4. A slat or lath for a blind, comprising, a web of stiff fabric material, having its opposite longitudinal edges piped, and grommet plates disposed transversely of and for the width of the web, each plate having its opposite ends respectively clinched about the edge piping.

HARRY G. BALTHASAR.
